(57) **CLAIM**

The ornamental design for a barnacle scraper, as shown and described.

DESCRIPTION

FIG. 1 is an isometric top view of a barnacle scraper showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof; and,

FIG. 7 is a top view thereof showing my design.

The broken lines in the figures depict portions of the barnacle scraper that form no part of the claimed design.
